(71) Applicant: **Wired Coliving SA**, Geneva (CH)

* cited by examiner

(72) Inventor: **Régis Dajczman**, Troyes (FR)

Primary Examiner — Khawaja Anwar

(**) Term: **15 Years**

(21) Appl. No.: **35/519,683**

(57) **CLAIM**

(22) Filed: **Nov. 28, 2023**

The ornamental design for an audio and video apparatus for reproducing sounds or images, as shown and described.

(80) **Hague Agreement Data**

DESCRIPTION

Int. Filing Date: **Nov. 28, 2023**

Int. Reg. No.: **DM/234404**

Int. Reg. Date: **Nov. 28, 2023**

Int. Reg. Pub. Date: **Jan. 19, 2024**

(51) **LOC (15) Cl.** **14-03**
